UNITED STATES PATENT OFFICE.

ERNEST MARVIN WHITTINGTON, OF NASHVILLE, TENNESSEE.

BLOTTER-HOLDER.

No. 821,812.

Specification of Letters Patent.

Patented May 29, 1906.

Application filed August 23, 1905. Serial No. 275,419.

To all whom it may concern:

Be it known that I, ERNEST MARVIN WHITTINGTON, a citizen of the United States, residing at Nashville, in the county of Davidson and State of Tennessee, have invented a new and useful Blotter-Holder, of which the following is a specification.

This invention is a blotter-holder by means of which a blotter can be attached and held upon the wrist of a person while writing in such a position that it will not interfere with the writing operation and by means of which the writing can be quickly and easily blotted without removing the pen from the hand and without necessitating the use of the other hand.

With these objects thus freely outlined my invention consists, essentially, in the employment of a spring-metal plate having clips at each end adapted to grasp and hold the blotter to the under side of the plate an adjustable strap for fastening the said plate to the wrist of the writer.

The invention consists also in certain details of construction hereinafter fully described, and pointed out in the claim.

In the drawings forming a part of this specification, Figure 1 is a view showing the practical application of my invention. Fig. 2 is a detail perspective view of the device disconnected from the wrist, the blotter being shown by the dotted lines; and Fig. 3 is an inverted plan view of the blotter-carrying plate.

In carrying out my invention I employ a thin metal plate A essentially rectangular in shape and of any convenient size, said plate being curved, as shown, and at each end is provided with integral clips B, which are bent back upon the under side of the plate A and are adjusted to securely hold the blotter C, the ends of the clips being bent slightly away from the plate at their free ends, as most clearly shown at B' in Fig. 3. The plate is split longitudinally adjacent one end, as shown at D, and the intervening portion E is

punched up and has a ring F connected thereto, and to this ring is attached one end of an adjustable strap G, opposite end of which carries a ring H, which is adapted to fit over 50 the finger I, punched from the plate and adjacent the opposite ends thereof, the free end of said finger projecting toward the adjacent end of the plate.

As before stated, plate A carries a blotter 55 C upon the under side thereof, and this plate is curved between its ends in order to fit the under side of the wrist, and the adjustable strap G passes over the upper side of the wrist and the ring H, hooked upon the finger 60 I. The device is then ready for use, and while held in this position the writing operation can be carried on and then by throwing the hand up the blotter can be brought into 65 operation, and in this manner the operations of writing and blotting can be carried on with ease and rapidity.

It can thus be seen that I provide a cheap, simple, and efficient appliance which will completely avoid the necessity of laying down 70 the pen or use the other hand for the purpose of blotting.

Having thus fully described my invention, what I claim as new, and desire to secure by Letters Patent, is—

A blotter-holder comprising a metal plate having integral clips at each end, said clips being bent back upon the under side of the plate and adapted to hold a blotter, an upwardly-extending loop punched from the 80 plate adjacent one end, a finger punched from the plate adjacent the opposite end, a ring fastened upon the said loop, and an adjustable strap connected to said ring and carrying a ring at its opposite end adapted 85 to engage said finger, all of said parts being arranged substantially as described.

ERNEST MARVIN WHITTINGTON.
